ANÆSTHETIC

Meyer L. Axelrod, Cleveland, Ohio, assignor of
fifty per cent to Harry Fraiberg, Cleveland,
Ohio

No Drawing. Application December 5, 1930
Serial No. 500,427

12 Claims. (Cl. 167—52)

My invention relates to improvements in hypnotic compounds, particularly analgesics and anæsthetics. In the administration of anæsthetics or analgesics, particularly for obstetrical operations, the usual practice has been to await until a certain amount of dilation of the cervix has taken place before administering the particular anæsthetic. It is common knowledge that the labor pains prior to the aforesaid dilation are 5 excruciating but may be relieved by the use of morphine or similar narcotics. However, such administrations are apt to have an undesired effect upon the patient and the child and does not always serve the intended purpose.

10 It is therefore one of the objects of my invention to provide a hypnotic compound which may be administered to the patient in the first stage of labor to permit uterine contractions and relieve the initial pains as well as the pains in the other 15 stages of labor.

Still another object of my invention is to provide an anæsthetic which may be easily and safely administered to the patient and which tends to eliminate the nervous condition which sometimes 20 accompany the administration of anæsthetics.

Another object of my invention is to provide an anæsthetic which may be administered during the first stages of labor and which is sufficiently lasting 25 in its effects to maintain the patient under its analgesic influence throughout the entire delivery.

Still other objects and uses of my new compound will become apparent from the following 30 description thereof.

I am aware that ether and oil with quinine have been heretofore administered to the patient by rectal instillation for obtaining analgesia; however, as previously stated, this administration 35 cannot be applied with success to the patient until after the first stages of labor have passed because of the short duration of its effect. I am also aware that barbiturates have been used with inhalation anæsthetics. I believe the use of the 40 barbiturates in the manner which I am about to disclose, is distinctly new. There are at the present time, a number of commercial barbiturates, some of which better suit themselves than others, to my particular compound. Among the more 45 useful barbiturates I have used are the following:

Nembutal (acid form)—ethyl (1-methyl butyl) barbituric acid.

Neonal—n-butyl ethyl barbituric acid.

Allonal—allyl isopropyl barbituric acid plus 50 amidopyrine.

Dial—diallyl barbituric acid.

Phanodorn—cyclohexenyl ethyl barbituric acid.

Amytal—isoamyl ethyl barbituric acid.

Ipral (acid form)—ethyl isopropyl barbituric acid.

Pernokton—secondary butyl bromallyl barbituric acid.

Phenobarbital—phenyl ethyl barbituric acid (Luminal).

Barbital—diethyl barbituric acid (Veronal).

In actual use, the patient is first given enemas until the return is clear, after which the barbituric preparation is instilled. The instillation of the barbituric compound may be preceded by an ounce of plain oil, also vaseline is applied to the 70 anus to prevent possible irritation should the compound be expelled. A slow uniform rate of instillation is established and the mixture permitted to enter the colon between uterine contractions.

The compound may include a mixture of mineral oil, ether, quinine and a barbiturate. The oil used may be either a mineral oil or vegetable oil such as olive oil. However, mineral oil is preferred as it does not tend to turn rancid. It is 75 also to be understood that the proportions of the ingredients in the compound may be varied to procure different degrees of anæsthesia.

I have observed in my various experiences that the solution can be made either with or without the aid of solvents other than the ether. In some ether the alcohol content is relatively high and therefore the quinine is more expeditiously put into solution. I also find that the quinine may be more quickly put into solution by using a 80 small amount of other solvents, such as ethyl alcohol, and when so used, I find that approximately three fluid drams of ethyl alcohol in a four fluid ounce solution of the compound is sufficient for all purposes of solubility.

I have found that a mixture of 1½ ounces mineral oil, 2½ ounces ether, 20 grains quinine alkaloid, together with a mixture of two barbiturates which are known to the profession as nembutal (acid form) and neonal, which barbiturates are ethyl (1-methyl butyl) barbituric acid, and n-butyl ethyl barbituric acid respectively, in the proportion of 8 grains nembutal (acid form) and 5 grains neonal produce a very 90 satisfactory result. I find that a combination of two or more barbiturates as described is sometimes desirable. The effect is not additive but due to the synergistic action between the two barbiturates, each barbiturate enhances the action 95 of the other, causing a substantially different 100 105 110

effect than is found from the use of either one alone. In the foregoing example ethyl (1-methyl-butyl) barbituric acid is representative of a quick acting barbiturate which takes effect very shortly after administration, whereas the other is representative of a relatively slow acting barbiturate which in this instance may involve twice as much time before it becomes effective. This mixture may be administered as previously described and 10 is particularly adaptable for analgesia during childbirth. Upon instillation of the above dosage, the average patient is susceptible to from 10 to 18 hours of complete amnesia and analgesia.

15 A compound made in accordance with my invention, from which the quinine is omitted may also be used for surgery. A particular combination for such use may be 2½ ounces ether, 1½ ounces mineral oil and 10 grains of nembutal. It is very apparent that the increased proportions 20 of the barbiturate will give more complete anaesthesia. The dosage may be regulated according to body weight, a patient weighing 130 pounds or over receiving the full 4 ounce mixture; those between 100 and 130 pounds receiving approximately 25 ¾ of the contents and those under 100 pounds receiving ½ of the contents.

In actual use it has been found that the patient usually becomes drowsy within 30 minutes and gradually goes into a deep slumber. In time, (1 hour) most patients can be aroused but with great difficulty and the uterine contractions appear to be accelerated rather than interfered with. The dosage of the barbiturates may in some cases be regulated in such a manner that a supplemental 30 anaesthesia may be required. The use of a compound as described, eliminates the use of drugs which may seriously affect the baby or patient. It will also reduce the post operative need of narcotics. The pulse, respiration and blood pressure are not materially affected. The blood loss 40 is not affected. Uterine contractions are not interfered with and the patient has no recollection of labor pains. No undesirable after effects have been observed.

45 Having thus described my compound and its method of use, I am aware that the exact proportions of the various ingredients may be varied, and should be varied to suit different cases, but

that such variation is well within the precepts of the invention and such as may be understood to those experienced in such matters and does not depart from the spirit of my invention nor the scope of the appended claims.

80

I claim:

1. A hypnotic compound for rectal instillation comprising a solution of oil, ether and a barbiturate.

85

2. A hypnotic compound for rectal instillation comprising a mixture of oil and ether and an oil and ether soluble barbiturate.

90

3. A hypnotic compound for rectal instillation comprising a mixture of mineral oil and ether and an oil and ether soluble barbiturate.

4. A hypnotic compound for rectal instillation comprising a mixture of mineral oil and ether and a barbiturate.

95

5. A hypnotic compound for rectal instillation comprising a mixture of oil, ether and two or more of the barbiturates.

6. A hypnotic compound for rectal instillation comprising a mixture of oil, ether and oil and ether soluble barbiturates.

100

7. A hypnotic compound for rectal instillation comprising a mixture of oil, ether, and ethyl (1-methyl butyl) barbituric acid-and n-butyl-ethyl-barbituric-acid.

105

8. A hypnotic compound for rectal instillation comprising a mixture of mineral oil, ether and ethyl (1-methyl butyl) barbituric-acid.

9. A hypnotic compound for rectal instillation comprising a mixture of mineral oil, ether and n-butyl-ethyl-barbituric-acid.

110

10. A hypnotic compound for rectal instillation comprising a mixture of mineral oil, ether and ethyl (1-methyl butyl) barbituric-acid and n-butyl-ethyl-barbituric-acid.

11. An analgesic comprising a mixture in the proportions—mineral oil 1½ ounces, ether 2½ ounces, and ethyl (1-methyl butyl) barbituric-acid 8 grains and n-butyl-ethyl-barbituric-acid 5 grains.

115

12. A hypnotic compound for rectal instillation comprising a mixture of mineral oil, ether, secondary-butyl-bromallyl barbituric acid and allyl-isopropyl-barbituric acid.
